DESIGN FOR A COOKY CUTTER

Stanley W. Price and Rebecca C. Price,
Oklahoma City, Okla.

Application November 6, 1947, Serial No. 142,319

Term of patent 3½ years

(Cl. D44—29)

To all whom it may concern:

Be it known that we, Stanley W. Price and Rebecca C. Price, citizens of the United States, residing at Oklahoma City, in the county of Oklahoma and State of Oklahoma, have invented a new, original, and ornamental Design for a Cooky Cutter, of which the following is a specification, reference being had to the accompanying drawings, forming part thereof.

We claim:

The ornamental design for a cooky cutter, substantially as shown.

STANLEY W. PRICE.
REBECCA C. PRICE.
